TRANSFORMER FAULT DETECTOR

Filed Sept. 30, 1932

Inventor:
David D. Coffin,
by Charles V. Weller
His Attorney.

UNITED STATES PATENT OFFICE

DAVID D. COFFIN, OF CAMDEN, NEW JERSEY, ASSIGNOR TO GENERAL ELECTRIC COMPANY, A CORPORATION OF NEW YORK

TRANSFORMER FAULT DETECTOR

Application filed September 30, 1932. Serial No. 635,591.

My invention relates to transformer fault detectors. There is occasionally a failure or breakdown of some part of the insulation of a transformer. The failure may be due 5 to abnormally high voltage conditions or to a defect in the insulation. There may be a sudden development of a serious fault but it often happens that a fault first starts as a very slight defect which does not interfere 10 at all with the normal operation of the transformer and which remains undetected for a considerable period of time. Such a slight defect may become more serious, however, and finally result in a serious breakdown 15 of the insulation. The general object of the invention is to provide an improved arrangement for detecting and indicating the presence of a slight defect in the transformer insulation so that the defect may be re- 20 paired before serious injury occurs to the transformer.

The invention will be explained more fully in the following description taken in connection with the accompanying drawing 25 in which Fig. 1 is a view, partly in section, of a transformer provided with a fault detector constructed and arranged in accordance with the invention; Fig. 2 is a sectional view on the line 2—2 of Fig. 1; Fig. 3 is a sectional view on the line 3—3 of Fig. 1; and Fig. 4 is an explanatory perspective view of a section of the transformer core and the fault detector.

Like reference characters indicate similar 25 parts in the different figures of the drawing.

The transformer shown in the drawing includes a magnetic core 10 having two winding legs 11 and 12, each winding leg being surrounded by primary and secondary 40 windings 13 which are insulated from each other and from the core. As shown most clearly in Fig. 2, the windings 13 are cylindrical in form and each of the core legs 11 and 12 have flat side surfaces so that there 45 is a small space 14 between each face of each core leg and the adjacent inner cylindrical surface of the inner winding 13.

A number of small flat coils 15 are secured in one of the spaces 14 beside each of 50 the winding legs 11 and 12 of the core, each

coil 15 being arranged with one of its flat faces close to the core leg and with its axis at a right angle to the axis of the core leg and the surrounding windings 13. The coils 15 on each core leg are connected in series 55 and distributed uniformly along the core leg and symmetrically with respect to its center. The coils 15 on each core leg may be held in place by a supporting strip 16 of insulating material such as wood. Each set 60 of series connected coils 15 is connected to a relay 17 having contacts which control some suitable instrument such as a bell 18.

The turns of a transformer winding are generally distributed uniformly along the 65 core leg which they surround and the leakage flux follows paths which are symmetrical with respect to the center of each core leg. Thus the leakage flux which passes through any one of the coils 15 is equal to 70 that which normally passes through the other coil 15 which is symmetrically located at the other side of the center of the adjacent core leg. The leakage flux thus induces a voltage in each coil 15 which is equal to 75 the voltage similarly induced in the other symmetrically located coil. Each coil 15 is also connected so that its voltage induced by the leakage flux is opposed to the voltage induced by the leakage flux in the other 80 symmetrically disposed coil. Thus the sum of the voltages of all the coils 15 is normally zero and the relay 17 is not affected.

If a small fault, such as a short circuit between two adjacent turns, develops in one of the windings 13, this will affect the distribution of the leakage flux so that the sum of the voltages in the coils is no longer zero. The unbalanced voltage causes the relay 17 85 to close its contacts and ring the bell 18, thus indicating the occurrence of the fault. The coils 15 are preferably disposed at the faces of the winding legs which are within the opening or window in the core as shown 90 in the drawing.

The invention provides a very simple and convenient arrangement for detecting and indicating faults in transformer windings before they become serious and it has been 100

found that the arrangement is very sensitive to small faults.

The invention has been explained by describing and illustrating a particular application thereof, but it will be apparent that changes may be made without departing from the spirit of the invention and the scope of the appended claims.

What I claim as new and desire to secure by Letters Patent of the United States is:

1. A transformer including a magnetic core having a winding leg, a winding surrounding said winding leg, a plurality of coils between said winding leg and said winding, each coil being disposed at one side of the winding leg with its axis at the right angle to that of the winding leg, and an instrument connected to said coils.
2. A transformer including a magnetic core having two winding legs, a winding surrounding each of said winding legs, a plurality of coils between each winding leg and its winding, each coil being disposed at the side of its winding leg within the core window and with its axis at a right angle to that of its winding leg, and means connected to said coils and responsive to the effects of a fault in said windings.
3. A transformer including a magnetic core having a winding leg, a winding surrounding said winding leg, a plurality of coils between said winding leg and said winding, each coil being disposed at one side of the winding leg with its axis at a right angle to that of the winding leg, and each coil being disposed symmetrically to another coil with respect to the center of the winding leg, and an instrument connected to said coils.
4. A transformer including a magnetic core having a winding leg, a winding surrounding said winding leg, a plurality of coils between said winding leg and said winding, each coil being disposed at one side of the winding leg with its axis at a right angle to that of the winding leg, each coil being disposed symmetrically to another coil with respect to the center of the winding leg, and each two symmetrically disposed coils being connected with their voltages normally opposed, and an instrument connected to said coils.

In witness whereof, I have hereunto set my hand.

DAVID D. COFFIN.
